(57) **CLAIM**

I claim the ornamental design for the truck sign dispenser, as shown.

DESCRIPTION

The present design relates to retractable sign designed to releasably attach to the rear end of a flat bed transport truck. FIG. 1 is a front perspective view from above of the truck sign dispenser of the present design.

FIG. 2 is a top plan view of the truck sign dispenser of the present design.

FIG. 3 is a left side elevation view of the truck sign dispenser of the present design.

FIG. 4 is a cross-sectional view taken in the direction of arrows 4—4 in FIG. 3 of the truck sign dispenser of the present design.

FIG. 5 is a right side elevation view of the truck sign dispenser of the present design; and,

FIG. 6 is a front elevational view of the truck sign dispenser of the present design.
